UNITED STATES PATENT OFFICE.

JOSEPH G. SWAIN AND MAX H. PADE, OF AKRON, OHIO, ASSIGNEES TO THE FIRESTONE STEEL PRODUCTS COMPANY, OF AKRON, OHIO, A CORPORATION OF OHIO.

MECHANICAL PLATING APPARATUS.

Application filed August 25, 1922. Serial No. 584,211.

To all whom it may concern:

Be it known that we, JOSEPH G. SWAIN and MAX H. PADE, citizens of the United States, residing at Akron, in the county of

5 Summit, State of Ohio, have invented certain new and useful Improvements in Mechanical Plating Apparatus, of which the following is a specification.

Our invention relates to improvements 10 in apparatus for use in electroplating annular objects such as tire rims or similar articles.

The purpose of our invention, broadly stated, is to provide a practical apparatus 15 adapted for continuous operation to transport and immerse a large number of articles in a plurality of baths whereby they are prepared for and subjected to an electroplating process, the operation of electroplating being carried on automatically.

Our invention is also directed toward providing a form of apparatus whereby such articles may be transported in a suspended 20 position by means particularly designed to occupy a relatively small amount of floor space.

An equally important object of our invention is to provide, in conjunction with means for suspending and transporting the 25 objects, devices for rotating the objects relative to the suspension means so that every portion of the object may be properly subjected to the action of an electroplating bath.

30 With these, and other objects in view as will presently appear, the invention resides in the construction and arrangement of cooperating elements, illustrated in their preferred assembly in the accompanying drawings, and set forth in detail in the following description.

In the drawings:

Figure 1 is a diagrammatic side elevational view illustrating, generally, a preferred 45 form of apparatus constructed in accordance with our invention;

Figure 2 is an enlarged fragmentary view, partly in section and partly in side elevation, illustrating an intermediate portion of the apparatus;

60 Figure 3 is a side elevational view, parts being broken out, illustrating that portion

of the apparatus contiguous the portion shown in Figure 2;

Figure 4 is a transverse sectional view, 55 on a further enlarged scale, taken on the line 4—4 of Figure 3;

Figure 5 is a detail transverse section of 60 a portion of one of the devices for suspending the articles; and

Figure 6 is a sectional view, taken on the line 6—6 of Figure 5.

The invention will now be described in detail. Referring to the drawings by number, 1 designates, as a whole, a frame 65 work comprising a series of pairs of upright supports 2, the supports of each pair being oppositely disposed and connected by suitably arranged braces as shown at 3. Each pair of uprights is suspended from 70 spaced parallel girders 4 arranged longitudinally of the apparatus which may in turn be supported in any suitable manner as by columns, two of which are shown at 4^a.

Beneath the supports 2, a number of tanks are arranged in a row to contain various liquids of the following character: Starting with the end of the apparatus, designated, in the drawings, "Loading," 5 80 is a tank for a soda or other solution suitable for use in preparing the articles for the plating process, 6 is a tank for a pickling solution, 7 and 8 are tanks for suitable spraying and cleaning solutions, 9 is a tank 85 for the electroplating fluid, and 10 and 11 are respectively spraying cabinets for use after the articles have been plated. The specific character of the fluids and solutions which these tanks are designed to contain forms no particular part of the present invention and therefore will not be entered into herein. It is sufficient to say that these tanks are for the purpose of containing 90 fluids or solutions of the general character above indicated and are arranged in succession and preferably in the order set forth relative to the loading and unloading ends of the apparatus.

Above the tanks, an endless conveyor 12 100 is arranged to travel, between opposed supports 2, upon a pair of superposed trackways which comprise, respectively, laterally spaced rails 13. The rails 13 are sup-

ported in any suitable manner upon the supports 2, for instance, by brackets 13^a shown in Figure 4. The rails 13 of the upper trackway are horizontal, whereas the 5 rails 13 of the lower trackway are constructed with undulating portions so arranged that the lower run of the conveyor descends over the tanks 5, 6, 8 and 9 and ascends over the ends of the tanks 6, and 10 8 and 9 to lift the objects carried thereon out of the tanks. Likewise the rails 13 of the lower trackway are constructed with elevated portions in the spray cabinets 7, 15 10 and 11. At suitable points, over the plating tank 9, the rails 13 of the lower trackway are provided with spaced pairs of arcuate rises, one rise of each pair being shown at 14. The rises of each pair are oppositely disposed, as will be understood 20 without further explanation. These rises serve a purpose presently set forth.

The conveyor 12 comprises duplicate endless chains 15 of any suitable construction, adapted respectively to travel upon superposed rails 13 of each trackway, the chains 15 being held in laterally spaced relation at regular intervals by cross bars 15^a carrying rollers 15^b which travel on the rails 13.

Cross shafts 16 and 17 are journaled respectively at opposite ends of the frame 1, one of which, preferably 17, is driven by means of a sprocket wheel 18 fast thereon and meshing with a driven pinion 19. The pinion 19 may be driven in any desired 30 manner. Each shaft 16 and 17 is provided with spaced sprockets, one of which is shown at 20 in each instance, which support the loop of the conveyor chains 14 at points above the tanks. Idler sprockets 21 are 35 provided at suitable points over the rails 13 of the lower trackway adapted to guide the conveyor chains as they ascend and descend over the tanks 5, 6, 7, 8, 9, 10 and 11. Each cross bar 15 carries a pair of duplicate 40 swinging brackets 22 adapted respectively to suspend the objects from the conveyor 12. The brackets of each bar are mounted one upon each side of the center thereof and are constructed as follows: Each bracket is 45 formed with a depending bifurcated portion 23 which, at its upper end, terminates in a hook 24 adapted to take over a longitudinally split sleeve 25 that is clamped upon the bar. Between the bar and the 50 sleeve 25 a suitable insulating sleeve 26 is interposed for a purpose presently apparent. The sleeve 25 is flanged adjacent each end thereof, whereby the bracket 22 is prevented from lateral play upon the bar. The 55 bifurcated ends 23 of the bracket are arranged in a transverse plane with respect to the conveyor, and are outwardly and upwardly turned to provide hooked portions 60 26^a upon which the annular object may be 65 suspended for both vertical and rotary

movement thereon, a recess 26^b being provided at the lowermost portion of the hook to permit passage of any projection, such as a driving lug, usually found on the underside of demountable rims. By means of this 70 construction, each bracket is adapted to support a pair of rims or other objects in position to swing about the bar 15 for a particular purpose presently apparent. As will be noted, the brackets are relatively arranged 75 to support the rims or other objects in parallel rows. Above the bar the hook 24 of each bracket 22 is provided with spaced upstanding ears 27. A contact brush 28 is pivotally mounted intermediate its ends between the 80 ears 27 of each bracket to swing in a vertical plane. One end of the brush 28 is counterweighted, as at 29, so that the other end is normally thrown upwardly.

The brushes 28 are designed to engage a 85 pair of horizontal contact rails 30 arranged longitudinally over the tank 9 and connected in any suitable manner to a source of electrical energy. In this instance, a cross bar 31 connects the rails 30 with a bus bar 32, 90 as shown in Figure 4 of the drawings. The contact rails are supported in such manner upon the frame 1 that they are insulated therefrom, as indicated at 33 of Figure 4. As shown in Figure 2, they are provided 95 with spaced rises 34 directly below the rises in the rails 13.

A plurality of rods 35 are supported longitudinally of the tank 9, adjacent its upper edge, in any suitable manner, upon which a number of anodes 36 may be suspended in parallel rows extending longitudinally of the tank. A suitable number of rows of anodes may be provided so that each longitudinal row of rims passes directly between two rows of anodes. Preferably the tank 9 is surrounded by a filler layer of suitable material designated 37 in the drawings, and is supported on insulating blocks 37^a. 100

Within the tank 9 a plurality of adjustable shoes 38 are arranged in rows extending transversely of the tank, one row of shoes being directly below each pair of rises 14 in the rails 13. These shoes 38 of each row are arranged at such intervals transversely 115 of the tank that they are disposed in the path of travel of the rows of annular objects, as will be seen by reference to Figure 4 of the drawings.

The shoes 38 of each row are slideable upon the floor of the tank, longitudinally thereof and in groups. In the present instance four shoes are utilized in each transverse row to correspond with the four rows of annular objects which may be electroplated upon the brackets 22 and are adjustable in groups of two. That is to say, each pair of shoes 38 upon one side of the longitudinal center of the tank is adjustable as a unit. To adjust the pairs of shoes 120 125 130

38, we provide a plurality of fulcrumed levers 38^a. Each lever is fulcrumed intermediate its length upon the tank 9, as at 38^b, to swing longitudinally of the tank. At its 5 lower end each lever 38^a carries a rod 38^c that extends transversely of the tank 9 and engages a pair of shoes 38 in such manner that when the lever is swung its associated pair of shoes will be slid longitudinally of 10 the tank. Levers 38^a are provided with detents 38^d and racks 38^e to hold them in adjusted position. Each shoe 38 comprises a vertical front face 39 constituting a portion of sufficient height to lift the annular 15 objects as they are drawn thereover and an inclined face 40. As the objects are drawn through the tank 9 their lower portions abut the vertical faces 39 of the shoes 38 and said objects are raised upon the hooks 26^a. As 20 they are drawn over the faces 39 they will gravitate and roll down the inclined faces 40. In this manner the rims or other annuli are intermittently turned and the portion of each formerly engaging the hook is rotated into position to be again immersed in 25 the electroplating fluid so that the entire surface of each article is subjected to the electroplating action. In order that objects of different sizes may be thus rotated, we 30 have provided the levers 38^a and their associated parts whereby the shoes may be adjusted to vary the distance of the vertical faces or high portions 39 of the shoes 38 relative to the rises 14. The rises and the 35 shoes 38 are so located that the lifting action of the shoes 38 will not operate to disengage the rims or other annuli from the hooks 26^a. The level of the electroplating fluid in the tank 9 is preferably maintained 40 at a sufficient height to substantially cover the annular objects, but in order to insure a uniform result of the plating process around the complete annulus, it has been found advisable that the portion of each 45 annulus in engagement with its associated hook be subjected to the electroplating process while said portion is free from such engagement. Furthermore it has been found that by rotating the articles in the 50 plating fluid, a more uniform result is obtained in the plating process.

The foregoing form and construction of apparatus will be found to possess many advantages. By its use a large number of 55 rims may be electroplated by merely placing them in double pairs upon the brackets 22 at the "loading" end of the apparatus and removing them at the "unloading" end. In the meantime they are mechanically 60 dipped in the proper solutions preparatory to the electroplating process, sprayed, cleaned, and immersed in the electroplating fluid, and again sprayed without being handled by the operators. Furthermore, it 65 will be seen that an apparatus of this type

may be constructed so that it will occupy a limited floor space.

The operation of our invention, it is believed, will be clear from the foregoing. An electric circuit is maintained which passes from the anodes to the rims or other objects suspended on the hooks and through the hooks and brushes to the rails 33. As each rim passes between rows of anodes, they will all receive a thorough and complete electroplate before leaving the tank 9.

The foregoing constitutes a detailed explanation of a preferred embodiment of our invention, but it is to be understood that changes in structural details, and modifications in the arrangement of the various parts may be resorted to without departing from the spirit of the invention unless otherwise specified by the claims appended hereto.

What we claim is:

1. Apparatus for use in electroplating annular objects comprising, in combination, a tank, a traveling conveyor adapted to transport the articles through the tank, a sloping runway in the tank and means for lifting the objects onto the runway and permitting them to roll down the same without becoming permanently disengaged from the conveyor.

2. Apparatus for use in electroplating annular objects comprising, in combination, a tank, a traveling conveyor adapted to transport the articles through the tank, a sloping runway in the tank, and means for lifting the articles in succession onto the runway to temporarily disengage them from the conveyor and to permit them to roll down said runway.

3. Apparatus for use in electroplating annular objects comprising, in combination, a tank, a traveling conveyor adapted to transport the articles through the tank, a sloping runway in the tank, and means for lifting the articles in succession onto the runway to temporarily disengage them from the conveyor and to permit them to roll down said runway, said conveyor being adapted to follow the rolling movement of said articles and to reengage them at the bottom of the runway.

4. Apparatus for use in electroplating annular objects comprising in combination, a plurality of horizontal fluid containing tanks, a traveling element adapted for transporting a series of the articles in an undulating path to pass them through said tanks, and means associated with one of the tanks for effecting a gravitational rotating movement of each article as it passes through said tank.

5. Apparatus for electroplating annular objects comprising in combination, a plurality of horizontal fluid containing tanks, a traveling conveyor for transporting a series of articles over the tanks, means for direct-

ing the travel of the conveyor in an undulating path to pass the articles through the tanks, and cooperating devices associated with the conveyor and one of said tanks 5 adapted to impart a gravitational rotary movement to each article as it passes through said tank.

6. Apparatus for electroplating annular objects comprising in combination, a plurality of horizontal fluid containing tanks, a 10 traveling conveyor for transporting a series of articles over the tanks, means for directing the travel of the conveyor in an undulating path to pass the articles through said tanks, and cooperating devices associated 15 with the conveyor and one of the tanks adapted to intermittently impart a gravitational rotary action to each article as it passes through said tank.

20 7. Apparatus for electroplating annular objects comprising in combination, a plurality of horizontal fluid containing tanks including an electroplating tank, a traveling conveyor adapted to transport the articles 25 over said tanks, means for directing the travel of the conveyor in an undulating path to pass the articles through the tanks, and cooperating devices associated with the conveyor and said electroplating tank adapted 30 to intermittently effect a gravitational rotary action of each article as it passes through said tank.

8. Apparatus for electroplating annular objects comprising in combination, a plurality of horizontal tanks, a traveling conveyor for transporting a series of the articles over the tanks, a trackway adapted to direct the travel of the conveyor in an undulating path to pass the articles through said tanks, a plurality 35 of arcuate rises in the trackway for intermittently lifting the conveyor in its travel over one of the tanks, swinging members depending from the conveyor adapted to support the articles by engagement with 40 their inner peripheries only, and a plurality of members in the tank adapted to engage the lower portion of each article and to lift it to a greater height than that to which said conveyor is lifted said members being adjustable in the path of travel of the objects. 45

50 9. Apparatus for electroplating annular objects comprising in combination, a plurality of horizontal fluid containing tanks including an electroplating tank, a traveling conveyor adapted to transport the articles over the tanks, a trackway adapted to direct the travel of the conveyor in an undulating path to pass the articles through the tanks, a plurality 55 of arcuate rises in the trackway over the electroplating tank for intermittently lifting the conveyor, swinging devices depending from the conveyor adapted to support the articles in position to be lifted and rotated relative to said devices, and 60 means in said tank for lifting said articles 65

in advance of said rises whereby they are rotated on said depending devices.

10. Apparatus for electroplating annular objects comprising in combination, a plurality of horizontal fluid containing tanks, a 70 conveyor adapted to travel over said tanks, a trackway adapted to direct the travel of the conveyor in an undulating path over said tanks, a plurality of rises in the trackway for intermittently lifting the conveyor over 75 one of the tanks, depending devices on the conveyor adapted to suspend the articles in position to be rotated thereon, means in said tank adapted to impart a lifting action to said articles in advance of said rises, a contact rail over said tank, and a brush member upon each device normally engaging said rail.

11. Apparatus for electroplating annular objects comprising in combination, a plurality of horizontal tanks including an electroplating tank, a traveling conveyor for transporting the articles over said tanks, a trackway adapted to direct the conveyor in an undulating path to pass the articles through 90 said tanks, devices upon the conveyor for suspending the articles therefrom in position to be lifted and rotated, means in said tank for intermittently lifting the articles upon 95 said devices, a contact rail over said tank, anodes in said tank, and a pivoted brush on each device adapted to normally engage said rail.

12. Apparatus for electroplating annular objects comprising, in combination, a plurality of fluid containing tanks, means for suspending and transporting a series of annular objects so that they will pass successively through the tanks, and means in one tank arranged to temporarily disengage the articles 100 from said first means and to effect a gravitational rolling movement thereof prior to reengagement therewith.

13. An apparatus for electroplating annular objects comprising, an electroplating 110 bath, a conveyor over the bath, hooks extending from the conveyor for supporting the objects to be plated, an electrical conductor over the bath, and brushes associated with said hooks and adapted to yieldingly 115 contact said conductor.

14. An apparatus for electroplating rims or similar objects comprising, an electroplating bath, a conveyor parallel to said bath, means on the conveyor for suspending the objects in the bath, a device for lifting and rotating the objects while in the bath, and means to elevate the conveyor during the lifting and rotating of the objects. 120

15. Apparatus for electroplating annular objects including in combination, a fluid containing electroplating tank, means for transporting a series of articles over the tank in an undulating path to immerse them in said fluid and withdraw them therefrom, 125 130

and means in the tank cooperating with said first means to effect a step by step rotation of said articles and comprising a plurality of inclined runways adapted for adjustment in the path of travel of the objects.

16. Apparatus for electroplating annular objects including in combination, a fluid containing electroplating tank, means for transporting a series of articles in suspended 10 position through said tank and in an undulating path, and means in the tank cooperating with said first means to effect a step by step rotation of said articles and comprising a plurality of runways arranged 15 in the path of travel of the objects.

17. Apparatus for electroplating annular objects comprising in combination, a plurality of tanks, a traveling conveyor for transporting a series of articles over the 20 tanks, a trackway adapted to direct the travel of the conveyor in an undulating path to pass the articles through said tanks, a plurality of arcuate rises in the trackway for intermittently lifting the conveyor in 25 its travel over one of the tanks, swinging members depending from the conveyor adapted to support the articles by engagement with their inner peripheries only, and a plurality of members in the tank adapted 30 to engage the lower portion of each article and to lift it to a height greater than that to which said conveyor is lifted.

18. Apparatus for electroplating annular objects comprising in combination, a plurality of horizontal fluid containing tanks including an electroplating tank, a traveling conveyor adapted to transport the articles over the tanks, a trackway adapted to direct the travel of the conveyor in an un- 35

dulating path to pass the articles through 40 the tanks, a plurality of arcuate rises in the trackway over the electroplating tank for intermittently lifting the conveyor, swinging devices depending from the conveyor adapted to support the articles in position to 45 be lifted and rotated relative to said devices, and means in said tank for lifting said articles whereby they are rotated on said depending devices.

19. Apparatus for electroplating annular objects comprising in combination, a plurality of horizontal tanks including an electroplating tank, a traveling conveyor for transporting the articles over said tanks, a trackway adapted to direct the conveyor in 55 an undulating path to pass the articles through said tanks, devices upon the conveyor for suspending the articles therefrom in position to be lifted and rotated, means in 60 said tank for intermittently lifting the articles upon said devices, a contact rail over said tank, anodes in said tank, a brush on each device, and means to yieldingly urge each brush into engagement with said rail.

20. Apparatus for electroplating annular objects including in combination, a fluid containing electroplating tank, means for transporting a series of articles over the tank in an undulating path to immerse them in said fluid and withdraw them therefrom, and means in the tank cooperating with said first means to effect a step by step rotation of said articles and comprising a plurality of inclined runways in the path of travel of the objects. 65 70
